(57) **CLAIM**

The ornamental design for a modular refrigerator, as shown and described.

DESCRIPTION

FIG. 1 is a right front perspective view of the design of the modular refrigerator;

FIG. 2 is a front elevational view thereof. The ornamental design is not visible in a rear view, top plan view or bottom view;

FIG. 3 is a right side elevational view thereof, the left side elevational view being a mirror image; and,

FIG. 4 is an enlarged view of the pattern on the modular refrigerator door of the embodiment of FIG. 1.

The characteristic feature of the ornamental design resides in the use of a pattern on the modular refrigerator door. One embodiment of a pattern according to the ornamental design is shown in FIGS. 1-4.

Those portions of modular refrigerator in broken lines, specifically the surfaces of the modular refrigerator at the top and bottom edges of the door and surfaces extending back from the door including other surfaces of the modular refrigerator are not part of the claimed invention.
